(57) **CLAIM**

The ornamental design for a toy having foldable portions, as shown and described.

DESCRIPTION

FIG. 1 is a front perspective view of a toy having foldable portions according to the present invention.

FIG. 2 is a rear perspective view of the toy having foldable portions illustrated in FIG. 1.

FIG. 3 is a front elevation view of the toy having foldable portions illustrated in FIG. 1.

FIG. 4 is a rear elevation view of the toy having foldable portions illustrated in FIG. 1.

FIG. 5 is a side elevation view of the toy having foldable portions illustrated in FIG. 1.

FIG. 6 is another side elevation view of the toy having foldable portions illustrated in FIG. 1.

FIG. 7 is a top plan view of the toy having foldable portions illustrated in FIG. 1.

FIG. 8 is a bottom plan view of the toy having foldable portions illustrated in FIG. 1.

FIG. 9 is a front elevation view of the toy having foldable portions illustrated in FIG. 1 and having portions of the toy positioned in a folded position.

FIG. 10 is a rear elevation view of the toy having foldable portions illustrated in FIG. 1 and having portions of the toy positioned in a folded position.

FIG. 11 is a side elevation view of the toy having foldable portions illustrated in FIG. 1 and having portions of the toy positioned in a folded position.

FIG. 12 is another side elevation view of the toy having foldable portions illustrated in FIG. 1 and having portions of the toy positioned in a folded position.

FIG. 13 is a top plan view of the toy having foldable portions illustrated in FIG. 1 and having portions of the toy positioned in a folded position; and,

FIG. 14 is a bottom plan view of the toy having foldable portions illustrated in FIG. 1 and having portions of the toy positioned in a folded position.

1 Claim, 14 Drawing Sheets
